ROLL SUPPORTING TYPEWRITER
ATTACHMENT

Morris C. Duncan, Russellville, Ky.

Application November 21, 1947, Serial No. 787,443

4 Claims. (Cl. 242—55.3)

1

This invention relates to improvements in typewriter accessories.

An object of the invention is to provide an improved gummed label supporting accessory for a typewriter.

Another object of the invention is to provide an improved support for holding a plurality of rolls of gummed labels in position adjacent a typewriter where they may be instantly and efficiently fed into the typewriter, as for example when a pharmacist has to prepare a label for a bottle of medicine.

A further object of the invention is to provide an improved support for rotatably supporting a series of differently sized rolls of gummed labels in position near a typewriter where any roll of labels may be quickly inserted in the typewriter for typing the necessary information thereon.

A still further object of the invention is to provide an improved typewriter accessory for supporting rolls of gummed labels near a typewriter, said accessory being highly efficient in operation, and relatively inexpensive to manufacture and produce.

Another object of this invention is to provide supporting means of the character described and having a standard which is adjustable as to length so that the device may be adjusted in height for use with different standard typewriters and the typewriters of portable character.

Other objects will appear as the description proceeds.

In the accompanying drawings which form a part of this application:

Figure 1 is a side elevation of the improved accessory shown adjacent a typewriter;

Figure 2 is a sectional view taken on the line 2—2 of Figure 1;

Figure 3 is a top plan view of the improved accessory;

Figure 4 is an exploded view of the main vertical supporting standard for the accessory; and,

Figure 5 is a sectional view taken on the line 5—5 of Figure 3.

Like characters of reference are used throughout the following specification and the accompanying drawings to designate corresponding parts.

In carrying out the invention, there is provided a weighted base 1, shown of circular shape and formed with a centrally disposed internally threaded socket 2.

A sectional three piece vertical supporting standard is provided and comprises an externally threaded lower thimble section 3 adapted to be

adjustably threaded in the threaded socket 2 and held in the desired vertical adjustment by the surrounding lock nut 4. The upper end of the thimble section 3 is recessed and internally threaded at 5 for receiving the externally threaded reduced end 6 of the central thimble section 7. The upper end of the central thimble section 7 is recessed and internally threaded at its upper end as at 8.

10 A top section 9 is formed with a reduced threaded shank 10 on its lower end for threading into the threaded upper end 8 of the central thimble section 7.

An annular recess 11 is formed about the upper 15 end of the top section 9, and is adapted to receive the locking ring or washer 12 which is preferably split.

A bearing head 13 is provided with a central bore 14 extending upwardly therein, terminating 20 in the arcuate seat 15 in which a ball bearing 16 placed on top of the top section 9 of the standard before it is inserted in the central bore 14.

An annular recess 17 is formed in the wall of 25 the central bore 14 and receives a portion of the split locking ring or washer 12 when said parts are in assembled position.

A laterally extending annular flange 18 is formed integrally on the bearing head 13 and supports the circular table support 19 which is 30 formed with five cut-out notches 20 in its peripheral edge. The central section 7 may be removed to shorten the standard when the device is to be used in connection with a portable typewriter.

Radial arms 21 are formed on the head 13 and 35 engage the table support 19, being secured thereto by means of the bolts 22.

Oppositely disposed bearings 23 are mounted at the sides of the five notches 20 and support the shafts 24 upon which the spools 25 are rotatably 40 mounted, and which form the cores for the rolls of gummed labels 26 which are perforated at 27.

The attachment will be placed near a typewriter 28 and any one of the rolls of gummed labels 26 may be rotated into alinement for feeding 45 to the typewriter when instructions or data has to be typed thereon. Resilient fingers 29 will be supported on the table support 19 and will engage the outer surfaces of the rolls 26 to resiliently tension the same.

50 Thus it will be seen that separate labels will not have to be located and inserted in the typewriter each time one has to be filled in.

While the preferred embodiment of the instant invention has been illustrated and described, it will be understood that it is not in-

tended to limit the scope of the invention there-to, as many minor changes in detail of construction may be resorted to without departure from the spirit of the invention.

Having described the invention, what is claimed as new is:

1. A device of the character described including a weighted base, a sectional vertical standard adjustably supported on said base, a bearing head rotatably mounted on said standard, a supporting table having radial notches and supported by said bearing head, and pairs of opposing bearings on said table at the edges of said notches for supporting rolls of material rotatably mounted in said radial notches.

2. A device of the character described including a weighted base, a sectional threaded vertical standard adjustably supported by said base, a bearing head rotatably mounted on said standard, a ball bearing disposed between said head and standard, a radially notched supporting table supported by said bearing head, and pairs of opposing bearings on said table at the edges of said notches for supporting rolls of material rotatably mounted in said radial notches.

3. A device of the character described including a weighted base, a sectional threaded vertical standard adjustably supported by said base, an intermediate section of the standard being removable, a bearing head rotatably mounted on said standard, a supporting table having peripheral notches and supported by said bearing head, pairs of opposing bearings on said table at the

edges of said notches for supporting rolls of material rotatably mounted in said peripheral notches, and resilient tensioning fingers on said supporting table frictionally engageable with the peripheries of said rolls.

4. A device of the character described including a weighted base, a sectional threaded vertical standard adjustably supported by said base, a bearing head rotatably mounted on said standard, a bearing disposed between said head and standard, a radially notched supporting table supported by said bearing head, means for locking said bearing head upon said supporting standard, pairs of opposing bearings on said table at the edges of said notches, shafts rotatably mounted in said pairs of bearings whereby rolls of strip material rotatably mounted in said radial notches, and radially extending resilient tensioning fingers secured to said supporting table and frictionally engageable with the outer surfaces of said rolls.

MORRIS C. DUNCAN.
